(57) **CLAIM**

The ornamental design for a center console for automobile as shown and described.

DESCRIPTION

FIG. 1 is a perspective view of the center console for automobile showing my design;

FIG. 2 is a front elevation view thereof;

FIG. 3 is a left side view thereof;

FIG. 4 is a rear view thereof;

FIG. 5 is a right side view thereof; and,

FIG. 6 is a top plan view thereof.

Portions of the center console shown in broken lines form no part of the claimed design.
